UNITED STATES PATENT OFFICE.

LÉON DUVIGNAU DE LANNEAU, OF PARIS, FRANCE.

CAP FOR PROJECTILES.

No. 918,560.

Specification of Letters Patent.

Patented April 20, 1909.

Application filed August 22, 1908. Serial No. 449,826.

To all whom it may concern:

Be it known that I, LÉON DUVIGNAU DE LANNEAU, of the Republic of France, residing at 71 Boulevard Pereire, Paris, France, have invented new and useful Improvements 5 in Caps for Projectiles, of which the following is a specification.

The present invention has for its object a rigid form of cap intended for preserving 10 the fuses of projectiles.

There are in existence protecting devices constituted by a cap of soft metal such as lead. Their defects are known: On the one hand they are wanting in strength, while on 15 the other hand they do not form a perfect joint where the tearing-off wire passes, and finally they leave residues of metal in the fuse-regulating appliances. Attempts have been made to obviate these defects by using 20 a complex rigid cap, comprising a lower cup fixed to the fuse and which is torn off, for the purpose of removing the cap, by means of a tearing-off wire; the cap proper being closed over upon the edges of this cup with 25 the intermediary of a joint. Apart from its complexity, high cost and the difficulty of forming a tight joint owing to the multiplicity of joints, this method of capping presents the defect of necessitating a tear-off 30 wire like a lead cap and where this wire passes through the joint is necessarily defective. In addition to this, the severing of the cup by means of the tear-off wire is an operation attended with considerable difficulty and occupies too much time to be satisfactory with quick-fire guns.

The novel method of capping consists in principle of a rigid metal cap, in a single piece, provided with an external tear-off collar or projection, formed with the said cap 40 or firmly fitted to it; the lower edge of this cap is fixed, by closing over or crimping, into or beneath a groove or shoulder formed for that purpose either upon the ogive of 45 the projectile or upon the plate of the fuse, or finally on a ring clamped or fixed between the projectile and the fuse.

The accompanying drawing shows, by way of example, various embodiments of the invention.

In the embodiment illustrated in Figure 1, *a* designates the upper part of the ogive of a projectile and *b* is the fuse. The capping is effected by means of a rigid metal 55 cap *c* shaped in such a manner as to present at an appropriate point a supporting

collar for a tearing off tool. The collar *e* for the engagement of the cap *c* is formed at the summit of the ogive. It is upon this collar that the lower edge *f* of the cap is 60 engaged. The cap presents a shoulder *g* which bears upon the upper part *h* of said collar *e*.

In the example illustrated in Fig. 2, the collar *d* is formed by a ring fitted and 65 brazed to the cap proper *c*. The engaging shoulder *e* projects from the plate of the fuse *b*.

In the construction illustrated in Fig. 3, the engaging shoulder *e* is constituted by 70 the salient edge of a metal ring pressed home between the fuse *b* and the ogive *a*.

In the example illustrated in Fig. 4, the lower edge *f* of the capsule is lodged in a groove *e¹* formed on the edge of the ogive 75 and which leaves upon the latter a circular tongue *m* sufficiently yielding to permit of being closed over by pinching the said edge *f*.

In the example illustrated in Figs. 1, 2 80 and 3, a tight joint is obtained in the following manner. The contacting parts of the cap *c* and of the engaging shoulder *e* are lightly coated with varnish or paint before the cap is arranged in position; this 85 coat should not be sufficient to foul the regulating appliances of the fuse. After the envelop has been fitted, the joint with the projectile is covered with a layer of varnish or paint which still further insures 90 a good joint.

In the example illustrated in Fig. 4, the walls of the groove *e¹* are coated with varnish or paint before the cap is arranged in place.

95

It will be seen that in all cases the device comprises but a single joint between the cap and the projectile and that this joint can be rendered perfectly tight.

On firing, the envelop is torn away by 100 means of a key or a pivoting device.

What I claim and desire to secure by Letters Patent of the United States is:—

1. As a new article of manufacture, a cap 105 to protect the fuses of projectiles, formed of a single piece of metal united at one end to the projectile and provided with a shoulder to be engaged by a suitable decapping implement, substantially as described.

2. As a new article of manufacture, a cap 110 to protect the fuses of projectiles, formed of a single piece of rigid metal united at

its lower end to the projectile and having its surface provided with a shoulder to be engaged by a suitable decapping implement, substantially as described.

3. In combination, a projectile having means for engaging a cap, a rigid one piece metal cap having means for engaging the said engaging means of the projectile, and a shoulder on the cap adapted to be engaged

by a suitable decapping implement, substantially as described.

In testimony whereof I have signed my name to this specification in the presence of two subscribing witnesses.

LEON DUVIGNAU DE LANNEAU.
